CLAIM

We claim the ornamental design for a razor cover, as shown and described.

DESCRIPTION

FIG. 1 is a front perspective view of the razor cover in a closed configuration.

FIG. 2 is a front view thereof.

FIG. 3 is a back view thereof, opposite the view of FIG. 2.

FIG. 4 is a right side view thereof.

FIG. 5 is a left side view thereof, opposite the view of FIG. 4.

FIG. 6 is a top view thereof.

FIG. 7 is a bottom view thereof, opposite the view of FIG. 6.

FIG. 8 is a bottom perspective view thereof; and, FIG. 9 is a top perspective view of the razor cover in an open configuration.

The broken lines illustrate portions of the razor cover and form no part of the claimed design.

1 Claim, 7 Drawing Sheets
